US00D937505S

(12) **United States Design Patent** (10) **Patent No.:** **US D937,505 S**
(45) **Date of Patent:** **** Nov. 30, 2021**

(54) **DOGGIE SCOOP**

(71) Applicant: **Michael R. Miklosovic**, Brook Park, OH (US)

(72) Inventor: **Michael R. Miklosovic**, Brook Park, OH (US)

(**) Term: **15 Years**

(21) Appl. No.: **29/712,202**

(22) Filed: **Nov. 6, 2019**

(51) LOC (13) Cl. **30-99**

(52) **U.S. Cl.**

USPC **D30/162**

(58) **Field of Classification Search**
